UNITED STATES PATENT OFFICE.

CHARLES ERLANGER, OF BALTIMORE, MARYLAND.

DESIGN FOR A RE-ENFORCE FOR TROUSERS.

SPECIFICATION forming part of Design No. 17,794, dated October 18, 1887.

Application filed August 29, 1887. Serial No. 248,215. Term of patent 14 years.

To all whom it may concern:

Be it known that I, CHARLES ERLANGER, a citizen of the United States, residing at Baltimore, in the State of Maryland, have invented 5 a new and original Design for a Re-enforce for Trouser, of which the following is a specification, reference being had to the accompanying drawing, forming a part thereof.

Said drawing represents my newly-designed 10 re-enforce for trousers.

The leading feature of my design is a re-enforce substantially of the configuration of a vertical section of a pear, the upper and lower ends of which are in right lines parallel with 15 each other. Said shaped re-enforce has springing from its either side a leaf-shaped wing, B.

In the drawing, A represents the re-enforce proper, having the outline of the two sides as follows: an outwardly-inclining line from a 20 to a', and from a' to the lower point is a curve outwardly extending, as shown at 2. From the terminal points of the upper parts of the

side edges the re-enforce assumes a right line, 3, and from the lower terminal points it is shaped into another straight line, 4, parallel 25 with the upper line, 3. On either side and toward the base of the re-enforce is a leaf-shaped wing, B, the inner edge of each of which wings conforming in configuration to that portion of the re-enforce in alignment therewith. The 30 upper points of said wings reach to about midway of the length of the outer sides of the main member of the re-enforce, (see x x.)

I claim—

The design for a re-enforce for trousers herein 35 shown and described, consisting of fabric the perimeter of which is in the form of a vertical section of a pear, the upper and lower edges being in parallel horizontal lines, and having a leaf-shaped wing, B, on its either side.

CHARLES ERLANGER.
